MUSICAL INSTRUMENT

Victor H. Severy, Los Angeles, Calif., assignor to
 Central Commercial Company, Chicago, Ill., a
 corporation of Illinois

Application April 19, 1930. Serial No. 445,655

3 Claims. (Cl. 84—409)

This invention relates to a musical instrument and the general object of the invention is to provide a simple construction for a musical instrument which will be capable of producing music in pure tones and capable of being controlled by simple means such as an ordinary piano keyboard or through the agency of automatic controlling means of any type, for example, such as employed in automatic piano players.

10 One object of the present invention is to provide means for producing the tones corresponding to notes of any desired musical scale and to provide cooperating means for enabling the tone producing vibrations to be amplified and 15 translated through the agency of an electric current to produce the musical sounds so that they will be readily audible.

A further object of the invention is to provide a musical instrument in which a series of vibrators may be employed capable of vibrating at 20 different periods respectively, corresponding to different notes, and to provide simple means for utilizing the said vibrations to develop impulses, and to amplify the same, the general purpose being to insure purity of tone in the music produced.

25 A further object of the invention is to produce an instrument of this type in which the quality, that is, the timbre, or color of the musical notes may be varied at will.

30 Further objects of the invention will appear hereinafter.

The invention consists of novel parts and combinations of parts to be described hereinafter, all of which contribute to produce an efficient 35 musical instrument.

A preferred embodiment of the invention is described in the following specification, while the broad scope of the invention is pointed out in the appended claims.

40 In the drawings:

Figure 1 is a diagram illustrating a simple apparatus which may be employed for practicing my invention. This figure may be considered as illustrating the elemental unit from which a 45 musical instrument to produce any number of different tones may be constructed.

Figure 2 is also a diagram illustrating a plurality of vibrators combined with my apparatus and including electrical circuits enabling the apparatus to be completely controlled by means 50 such as a keyboard.

Figure 3 is a detail fragmentary view particularly illustrating the means for mounting the vibrator when the same is of the tuning fork 55 type.

Figure 4 is a perspective broken away and showing two vibrators of the tuning fork type mounted in a musical instrument and illustrating how my apparatus is adapted for use with hammers such as employed in an ordinary piano 60 action for actuating the vibrators to produce the music.

Figure 5 is a diagrammatic view illustrating details of an adaptation of the apparatus enabling the vibrators to be actuated and controlled by an electric circuit and in which the action of the vibrator is automatically damped.

Figure 6 is a vertical section taken about on the line 6—6 of Figure 5 and further illustrating details of the striker head which may be employed 70 to start the vibration of the vibrator.

Figure 7 is a diagrammatic illustration of the general character shown in Figure 2, but illustrating apparatus of the type shown in Figure 5 together with an automatic controlling device 75 such as a music roll or perforated web, and illustrating also how the same apparatus can be controlled when desired through the agency of keys on an automatic piano keyboard.

Figure 8 is a side elevation and partial section 80 through an electro-mechanical damper device such as illustrated in Figure 7.

Figure 9 is a diagrammatic view illustrating an application of the invention in which the 85 quality of notes produced may be controlled at will and illustrating a connection for enabling the music to be broadcast.

Figure 10 is a diagrammatic view illustrating the application of the invention to a reed type 90 of vibrator in which the vibrator is caused to vibrate without percussion.

Figure 11 is a diagrammatic view similar to Figure 10, but illustrating diagrammatically the application of the invention to the reed type of 95 vibrator actuated by percussion and in which the regenerating circuit illustrated in Figure 10 is also employed.

Before proceeding to a detailed description of the invention it should be stated that the apparatus includes a plurality of vibrators constructed to vibrate at different definite periods respectively corresponding to the different notes of a given scale. Any type of vibrator may be employed for this purpose, but in the present specification I have illustrated tuning forks used for this purpose. Such forks may be readily procured and are very dependable to vibrate at the definite period of the fork. Furthermore, they will maintain this property for long periods of 110

time. Such forks are now largely used for tuning musical instruments of different kinds.

My apparatus also includes means for developing electric impulses in an electric circuit to correspond with the vibrations of the vibrator, and these impulses may be employed directly in sound translating devices to produce the tone corresponding to the different vibrators.

I prefer, however, to employ amplifying means in connection with the circuit for amplifying the impulses, thereby enabling the pure tone of the vibrator to be reproduced in a readily audible tone.

Referring more particularly to the parts and particularly to Figure 1, 1 represents a tuning fork, the handle of which is tightly supported in a bracket 2, being embedded in a packing 3 adapted to absorb vibrations. Adjacent the tines 4 of this fork I mount electrical means which will be affected by the vibration of the tines. This means includes an electric coil 5 held fixed adjacent the tines and provided with an armature, the poles of which lie adjacent to the faces of the tines so that when the tines vibrate they will approach and recede from the poles of the armature. I prefer to provide an armature 6 in the coil located between the tines and with its end faces or poles quite close to the face of the tines but not so near as to be touched by the tines when their vibrations have the greatest amplitude.

The coil 5 is connected up with an electric circuit 7 including a battery 7a which is connected up with a sound translating device 8 such as a loud speaker. The circuit also includes the controller means capable of controlling the closing of the circuit so as to produce the tone of the vibrator in the loud speaker. The apparatus may include regenerating means, the operation of which is to employ the vibration of the fork to affect the electrical apparatus so as to build up the amplitude of the vibrations. In order to accomplish this I prefer to employ an electric device 9 having the essential characteristics of a device commonly called a pick-up. This device includes a small armature 10 in the form of a bar mounted to rock on a pivot 11 near its middle point, being held in position between pole pieces 12 and 13 carrying coils 14 which are connected into an electric circuit 15 excited by any suitable electric means, such as a battery 16. The bar 10 carries a coil 17 which is connected into a circuit 18 having a conductor 19 and a conductor 20 leading to the input side of an amplifier 21. Connected into the conductor 19 I provide a rheostat 22. The output side of the transformer is connected through conductors 23 and 24 to two series primary coils 25 and 26 of the transformer 27.

This transformer includes secondary coils 28 and 29 in the form of rheostats connected into the conductors 30 and 31 that form the sides of the circuit 7. The circuit 7 may be closed at will by any suitable controlling means, for example, a key 33 carrying an insulated contact that is connected to a conductor 34 leading to the loud speaker 8 and a fixed contact 35 that cooperates with the movable contact to close the circuit when the key is depressed.

In the operation of this apparatus, when the key is depressed the closing of the circuit through the transformer results in the development of current in the coil 5, thereby energizing the core 6 of the coil. The core therefore attracts the tines 4 of the fork. Due to the resiliency of the

fork, the tines will recede from the core 6. The movements of the tines, through a connection 36 from one of the tines to the bar 10, will cause a rocking of the bar 10 and coil 17 on the pivot 11. This rocking of the coil will generate impulses in the coils 14 which will be felt at the amplifier 21 which will cause impulses in the coils 25 and 26. These impulses, through the coils 28 and 29 will affect and amplify the impulses in the circuit 7 and in the coil 5. In this way, after the fork is started to vibrate, it will maintain itself in vibration and produce a continuous tone corresponding to its rate of vibration as long as the circuit remains closed at the contact 35.

The connection 36 is preferably of a slightly flexible or resilient character. Otherwise, it preferably includes one or more joints. The point at which the connection 36 touches or connects to the tine of the fork is preferably at a point on the tine that will vibrate. In other words, this connection should not be located at a node.

Apparatus of the character illustrated in Figure 1 can be readily utilized to construct the musical instrument as illustrated in Figure 2 in which I illustrate an instrument of this character having seven vibrators. In this view I illustrate two banks 37 and 38 of vibrators in the form of tuning forks 39. Corresponding to each fork I provide an electric coil 40 with an armature located between the tines of the fork connected by a circuit through wires 41 and 42 with a corresponding transformer 43. This is a balanced transformer of the type illustrated in Figure 1 comprising two pairs of oppositely disposed coils arranged as illustrated in Figure 1. Each transformer 43 is connected on the output side to two wires 44 and 45, the former of which runs to a corresponding key 46 of a keyboard 47 and connects to a switch operated by the key, as illustrated in the key 33 in Figure 1.

From the key a return wire 48 connects to a trunk wire 49 that leads to a sound translating device such as a loud speaker 50. The other side of the loud speaker is connected to a trunk wire 51 to which the wire 45 is attached. In addition to this, each fork 39 may be provided with a regenerating circuit, such as illustrated in Figure 1, including a pickup device 52 corresponding to each fork and having an oscillating coil such as the coil 17 (see Figure 1), the ends of which are connected to wires 53 and 54 that lead into a corresponding amplifier 55. This amplifier is connected by wires 56 and 57 with the input side of the transformer 43.

It will be seen that the arrangement of wiring in Figure 2 contains the elements of the wiring shown in Figure 1, but represents the different keys connected up to trunk wires 49 and 51 that lead to a common sound translating device or loud speaker. If desired, a plurality of loud speakers can be employed connected either in series or parallel between the two trunk wires 49 and 51, said speakers being adapted for faithful reproduction of sounds at different points on the musical scale employed.

The exciting coils of the pickup device 52 can all be connected in parallel between trunk wires 58 and 59 connected to opposite sides of a battery 60.

Instead of constructing the device so that the mere closing of a circuit by a key will produce a desired note, I may mount the forks in a frame capable of being actuated by hammers such as employed in a piano action for striking a piano string. This is illustrated in Figure 4 in which

61 and 62 represent two forks located adjacent to each other and mounted in a frame 63 and in a position to be struck by piano hammers 64 carried on levers 65 such as usually employed in 5 a piano action. These hammers 65 afford means for starting the vibration of the corresponding forks when given keys of the keyboard are struck. The vibration of the tines of the forks develop impulses in coils 66 set between the tines of the 10 forks as illustrated and thereby develop impulses in the circuit wires 67 and 68 that connect the ends of the coils with trunk wires 69 and 70 that lead over to amplifier 71 that is connected on its output side with a sound translating device, such 15 as the loud speaker 72.

Above the forks a damper rail 73 may be provided supported on operating levers 74 which normally hold the damper out of contact with the forks but which can be operated when depressed by any suitable means such as used in a 20 piano, to depress the damper onto the forks and stop their operation.

If desired, this construction may include a switch 75 which closes the circuit through the 25 wires 69 and 70 and through the amplifier 71.

If desired, the vibration of the forks can be produced through the medium of a blow struck by an electrically operated hammer. This arrangement is illustrated in Figure 5 in which 30 76 represents one of the tuning forks located directly over a corresponding electric hammer 77, said hammer including a solenoid coil 78 having a soft iron core 79 or its equivalent projecting from its low end and carrying a stem 80 of non-magnetizable metal at its upper end so that when current flows through the coil 78, the core 79 will be pulled up and cause a head 81 carried at the upper end of the stem 80, to strike the lower tine of the fork 76. The head 81 may 35 carry a cushion tip 82.

I prefer to provide means for automatically damping the vibration of each fork shortly after the hammer 77 has struck its blow. For this purpose, below the fork I provide an electrically 40 operated damper 83 comprising a pair of solenoid coils 84 that operate, when the current flows through them, to draw down an armature 85 and withdraw the damper head 86 from its normal contact with the tine.

The coils 84 are actuated at the same instant 45 that the electric hammer 77 is actuated, so that at the instant that the blow is struck by the hammer the damper head 86 will be out of contact with the fork. However, the damper head is immediately returned by a spring 87 to its normal raised position. The details of this electric 50 damper are illustrated more fully in Figure 8. Each coil 84 is provided with a fixed tubular pole piece 88 which operates as a guide for one 55 of the stems 89 of the armature 85. The lower ends of the pole pieces 88 rest at their lower ends on a bar 90 through which the stem 91 is guided. This stem extends down from the lower side of the armature 85 at its middle point and carries 60 the coil spring 87, already referred to. The parts in Figure 8 are shown in active operation with the head 86 slightly withdrawn from the under- 65 face 92 of the fork. As soon as the energizing current flowing through the coils 84 ceases, the 70 spring 87 immediately returns the head 86 unto contact with the fork. The coils 78 and the two coils 84 of the electric damper may be connected up in parallel in an electric circuit 93, including a battery 94 and a pair of normally open contacts 95 closed by the depression of a key 96

pivotedly mounted at 97, and carrying an insulating bridging contact 98 on its underside. This key is normally held raised by any suitable means, such as a spring 99.

Between the tines of the fork 76 a coil 100 is provided to perform the same function as the 80 coils 66 and the coils 5, already described.

If it is desired to have the electric hammer strike a quick blow and withdraw immediately from the fork, I may construct the head 81 as 85 illustrated in Figure 6. This view represents the head in the act of striking the fork. The head 81 is mounted with a lost motion connection on the upper end of the stem 80, said stem having an enlarged collar 101 on its upper end, and 90 that moves between the faces 102 and 103 on the head 81. With this construction of head it will be evident that when the stem 80 is actuated by the electric coil 78, the head 81 supported on the upper side of the collar 101 will be driven up 95 against the face 92 of the fork. The lost motion connection between the stem and the head enables the stem 80 to be stopped short of the position in which the collar 101 would force the head 81 against the face 92. In other words, the 100 blow can be struck by the head 81 advancing by reason of its own momentum. In order to enable the stem 80 to be stopped adjustably at any point desired, the lower end of the core 79 is threaded 105 to receive an adjustable nut 104 and a check nut 105.

If desired, the invention may be adapted for operating the vibrators through the medium of a control device of an automatic nature, such as the music rolls (perforated webs) of player 110 pianos. This is illustrated in Figure 7 in which 106 indicates such a perforated web running between two spools 107 across a tracker board 108. The tracker board has a perforation 109 corresponding to each fork or vibrator and each perforation is connected up by a tube 110 to a corresponding bellows 111, said bellows is normally maintained in collapsed state through the agency of a vacuum chamber or air pump connected up to a vacuum tube 112 that connects with the 115 bellows. When the perforation 113 in the web registers with its corresponding perforation 109 in the tracker board, the vacuum is broken and the air pressure admitted to the bellows causes 120 the movable side 114 of the bellows to move out and close a circuit 115 through the agency of a movable contact 116 on the bellows that comes against a relatively fixed contact 117 connected with the circuit 115. The circuit 115 includes 125 two conductors 118 and 119 which lead over and connect up to an electric hammer 120 and an electrical control damper 121 constructed and 130 wired as illustrated in Figure 5.

The circuit 115 may include a battery 122. The instrument includes a plurality of forks 123 each of which has a corresponding coil 124 located between its tines and connected up by wires 125 and 126 that connect to trunk wires 127 and 128. The amplifier 129 is provided connected to these 135 trunk wires by wires 130 and 131 and the output side of the amplifier is connected up to a sound translating device or loud speaker 132.

If desired, this instrument can be operated at will through the agency of a keyboard such as a 140 piano keyboard, the keys 133 of which are illustrated diagrammatically in Figure 7. These keys are constructed as illustrated in Figure 5 and when any key is depressed an insulated contact 134 carried by the key bridges two contacts on 135

the ends of wires 135 and 136 that connect respectively, to the wires 118 and 119.

I shall now describe briefly the general mode of operation of the apparatus. In the apparatus I illustrate in Figure 7 the forks 123 which may be vibrated either by the keys 133 of a keyboard or by an automatic control device, such as a perforated web 106. When operated by the web 106, when a perforation 113 in the web comes opposite a corresponding perforation in the tracker bar 109, the partial vacuum normally existing in the corresponding bellows 111 is broken, whereupon the moving side 111 of the bellows moves outwardly and brings contacts 116 and 117 into engagement, thereby closing circuit 115 which energizes the coils 120 and 121.

This causes the electrical hammer (see Figure 5) to drive its head 81 against the underside of the fork, thereby delivering a blow which starts the fork vibrating. At the moment that this occurs the coils 121 will have withdrawn the damper head 86 from contact with the lower tine of the fork. If the hammer head 81 is constructed as illustrated in Figure 6, the blow on the fork will be struck through the momentum of the head, which carries the head on after the stem 80 has been stopped through the operation of the adjustable stop nut 104 when the same strikes the lower head of the coil 78.

The vibration of the tines of the fork 123 causes impulses in the coil 124 corresponding to the active fork and these impulses, of course, will correspond in rate to the rate of vibration of the fork. In this way, impulses in the coil 124 are imparted to the trunk lines 127 and 128 that connect by wires 130 and 131 to the amplifier 129 which operates to impart amplified impulses at the same rate to the loud speaker 132.

Instead of employing the electrical hammers 77 constructed as illustrated in Figure 5, the apparatus illustrated in Figure 4 may be employed in which the forks are caused to vibrate by being struck with hammers 64 such as employed in an ordinary piano action.

Associated with the forks a damper 73 is provided for damping the action of the forks after they have been struck. The action of the forks 62 on their coils 66 in the apparatus shown in Figure 4 is the same as that described in connection with the operation of the apparatus illustrated in Figure 7.

The apparatus illustrated in Figures 4 and 7 is particularly adapted for producing music quite similar to that produced on an ordinary piano, that is to say, music in which the notes are not long sustained. The apparatus illustrated in Figures 1 and 2 is particularly adapted for producing continuous sustained notes of uniform loudness, that is to say, any note when sounded will continue to sound with a pure tone at a uniform loudness.

In the elemental apparatus illustrated in Figure 1 which shows the circuits corresponding to a single key of a keyboard, a regenerating effect is attained whereby the vibrations of the tines of the fork cooperate to increase the intensity of the impulses which started their vibration. In this construction, when the key 33 is depressed, a circuit is closed through the wires 31 and 34 and through the sound translating device 8, and this circuit also includes portions of the balancing coils 27 and 28 which are hand controlled rheostats, used to balance the impedance of the circuits of loud speakers with the pickup circuits.

The disturbance in the coils 25 and 26 is di-

vided equally as to periodicity but not as to resistance balance as the coil 5 which serves to keep the fork vibrating has not the same impedance in its circuit as the loud speaker 8.

The vibration of the fork is sustained by the little electric pickup feeding its small current pulsations from its coil 17 over the wires 19 and 20 into the input side of the amplifying device and out by wires connected from the output side of the transformer, to the conditioning or impedance balancing transformer to the loud speaker over the wires 30 and 34 through switch 33, and contacts 32 and 35. When this switch is closed the audible side of the circuit is connected and a continuous tone is heard. The primary or generating circuit is always generating timed electric impulses when the oscillator is started, but only is allowed expression into sound waves, through the loud speaker, when the audible circuit is closed by the keys, operable by the organ player.

In Figure 9 I illustrate an adaptation of the invention to the production of notes of different color, quality or timbre. In order to accomplish this I provide a plurality of vibrators, for example, tuning forks capable respectively of producing the fundamental and other partials of the different notes. The vibrators for each note are caused to operate in unison by the same means, for example, a single key. By any suitable means, for example, a switch, I determine which partials of the note will be produced. As illustrated in Figure 9, 133, 134 and 135 illustrate any three keys of a keyboard. Corresponding to the key 133 I provide a plurality of vibrators, 100 in the present instance, tuning forks 133a, 133b, 133c and 133d. The vibrator or fork 133a is capable when vibrating of producing the fundamental of the note corresponding to the key 133; the vibrators 133b, 133c and 133d will produce 115 the second, third and fourth partials of this note. These vibrators may be caused to vibrate by means such as illustrated in Figure 1, but in the present instance I have illustrated them as being vibrated by a percussion device or hammers 120 136 corresponding to each vibrator.

Corresponding to the key 134 I provide similar vibrators indicated generically by the numeral 137 which are all connected up and arranged in the same way as the vibrators corresponding to 125 the key 133. If desired, the vibrators may have regenerating means for giving increased volume to the note produced, including coils 138. Similar coils 139 are provided to correspond with the key 134 and likewise, as to the vibrators 140, that correspond to the key 135.

The corresponding partials are all connected together on branch circuits so that all the keys of the manual will combine the same partials, and switch means is employed so as to enable any number of the partials to be employed. For example, all of the second partials only may be sounded, or the second and third partials, omitting the fourth partials, etc. and any partial may be made to predominate in the note produced. In order to accomplish this I provide a switch 141 corresponding to the second partials and controlling movable contacts 142 which when closed, close a circuit from the ground through conductor 143 which connects with a main conductor 144 with branches 145 corresponding to electrically operated switches 146. Each switch 146, when energized, brings movable contact 147 together so as to close the branch 145 150

circuit through a corresponding wire 148 that is capable of energizing the electric hammers 136.

Corresponding to the second partials I provide a switch 149 that operates similarly to the switch 141 and when closed, closes all the electro-mechanical switches 150 that correspond to the second partials.

Similar switches 151 and 152 correspond to the third and fourth partials and close corresponding switches 153 and 154. When all of the partial switches are closed any of the keys 133, 134, 135 and any other key of the manual will produce a tone including the fundamental and the second, third and fourth partials.

15 If desired, manually operated switches 155 may be provided corresponding to all of the electric switches 146 and similar switches 156 and 157 may be provided in connection with the wiring connected with the keys 134 and 135. For the 20 purpose of illustration these switches are illustrated in Figure 9 as being controlled by three separate shafts, but in practice they can all be in line with each other and operated by a single shaft. Such a shaft should be provided with cams 25 or tappets 158 that bring the contact members of the switches together to close the circuit.

It should be understood that the apparatus and wiring for the two keys 134 and the other keys on the manual will be substantially the same as 30 the wiring and apparatus illustrated in connection with the key 133. If desired, each vibrator can be provided with a damper 158 similar to the dampers already described. When any key, for example the key 133, is depressed, current flows 35 from the ground at 159 through a switch 160 that becomes closed by the depression of the key and from this switch the current flows over a wire 161 and through the battery 162, and thence through a trunk wire 163 having branches 164 corresponding to the different switches 147, 150, 153 and 154. If all of these switches are closed, 40 all of the electric strikers 136 will be actuated to strike their corresponding vibrators or tuning forks, the current flowing from the coils of the 45 hammers to the ground at 165. If dampers 158 are employed the coils of these dampers are connected in parallel by wires 166, which are also grounded at 165.

The regenerating circuits for the different regenerating coils 138 are formed by means of wires 50 166 and 167 that connect respectively with two trunk wires 168 and 169, the ends of which connect up to an amplifier 170, the output side of which connects to a sound translating device such 55 as a loud speaker 171. If desired, one of these conductors, for example 168, may be provided with a hand controlled switch 172.

If desired, the apparatus may be employed for 60 broadcasting. This may be accomplished in a simple manner by connecting the wires 168 and 169 to a double knife switch 173 connected to an amplifier 174, the output side of said amplifier having a sending circuit grounded at 175 and connected through a rheostat 176 with a suitable 65 antenna 177.

In Figures 10 and 11 I illustrate the use of vibrators in the form of reeds connected with my apparatus. In Figure 10, 178 represents a reed 70 mounted on a vibration absorbing block 179 and provided on its side with a core 180 of a pickup device 181, said pickup device including a coil 182 connected at one end through wire 183 to one side of a switch 184 controlled by a key 185.

When this key is closed a circuit is closed by 75 a wire 186 leading from the switch and through

a wire 187 connected with the other end of the coil, through the input side of an amplifier 188; the output side of this amplifier is connected by wires 189 to a conditioning transformer 190, the output side of which is connected by wires 191 to a sound translating device or loud speaker 192. A regenerating coil 193 is connected by wires 194 to the conditioning transformer. The wiring of the conditioning transformer is substantially the same as that illustrated in connection with 80 Figure 1.

The reed 178 may be provided with an adjustable weight 195 mounted on an adjusting screw. By changing the position of this weight the vibrating time of the reed can be very accurately 90 tuned to produce its note accurately.

The core 180 moves between two exciting coils 196 energized by any suitable source of electricity such as a battery 197.

The wiring arrangement in Figure 11 is substantially the same as that described in connection with Figure 10 except that in this apparatus the reed 198 is operated by the percussion of a hammer head 199 which may be in the form of an electric hammer, the coil 200 of which is energized 100 by closing switch 201 through the agency of a key 202.

In the operation of the apparatus illustrated in Figures 10 and 11 the upward and downward motion of the core 180 of the pickup produces 105 variations in the current passing in the input side of the amplifier, thereby producing corresponding variations or impulses in the regenerator coils 193, thereby maintaining the reed in vibration. This apparatus will give a sustained note like that 110 produced by an organ.

The color and tonal gradations of the partials as produced in the apparatus illustrated in Figure 9 can be determined by two factors, namely, the size of the tuning fork and its pitch, or by the 115 resistance placed in the electric circuit wire passing through the coil of the electric hammer. In other words, the resistance in the hammer circuits can be regulated to determine whether the partial is weak or strong. In this way the color 120 of the tones can be readily controlled and this will enable the instrument to be adapted to reproduce the quality of different musical instruments characterized by the predominance of certain partials.

In Figure 1 I illustrate wires 203 and 204 corresponding to the wires illustrated in Figure 9. These wires 203 and 204 are trunk wires connected respectively to the different vibrator circuits. Between these wires 203 and 204 vibrators, such 130 as tuning forks 205, 206 and 207, for the different partials of the corresponding main tuning fork are provided, said "partial" tuning forks being sounded through the medium of coils 208, respectively. These coils 208 are connected into branch 135 wires 209, each having its own switch 210, and these branch wires 209, beyond the coils, connect up to a trunk return wire 211, one end of which is connected to the trunk 204.

Associated with each of the switches 141, 149, 140 151, and 152, I provide a battery 143a (see Figure 9) which is in the circuit closed by each switch.

The circuit wire 186 connects with the battery 186a (see Figure 10).

The circuit closed by the switch 201 that passes 145 through the transformer 202a is provided with a battery 202b.

It is a fact that the difference in musical notes sounded on different musical instruments is due to the variation in the partials which are included 150.

in the note and to their relative intensity. According to my invention I provide for combining the partials with any desired intensity, thereby enabling the instrument to produce musical notes having the same timbre or quality of notes sounded on different musical instruments. By way of example I have illustrated one of the circuit wires in Figure 9 as provided with means for controlling the intensity of one of the partials, namely, the partial corresponding to the tuning fork 133d. In order to accomplish this I provide the regenerating circuit wire 211 corresponding to this partial with a plurality of resistances 212 of different values, each resistance having a corresponding electrical switch 213.

These electrical switches are controlled at will through other switches, such as the switch 214. By closing any desired electric switch, the circuit from the wire 211 can be made to pass through any one of the different resistances 212, thereby controlling the volume of sound produced by this vibrator or tuning fork 133d. In practice, if desired, the corresponding regenerating circuit for every partial fork would have a corresponding selective resistance. In this way I can not only play any desired partial or combination of partials, but can, at will, give the partials the relative intensity necessary to give the different quality of tones corresponding to different orchestral instruments.

In addition to this, if desired, the intensity of the partials may be controlled by regulating the force of the blow delivered by electric hammers, such as the hammer 136. This may be accomplished in a manner similar to that just described by providing a plurality of resistances 215 of different value connected into one of the circuit wires, such as the circuit wire 148'. Between the corresponding switch 154 and the electrical hammer corresponding to this wire I provide three electric switches 216 corresponding to the different resistances 215. Each electric switch is controlled by a corresponding circuit 217 having its corresponding switch. Evidently, by closing the proper switch any one of the resistances 215 can be drawn into the circuit. In practice all of the wires 148 would be provided with such relative resistances.

It is understood that the embodiment of the invention described herein is only one of the many embodiments this invention may take, and I do not wish to be limited in the practice of

the invention, nor in the claims, to the particular embodiment set forth.

I claim:

1. In a musical instrument, the combination of a plurality of resilient vibrators capable of vibrating at different periods, electro-mechanical means including a moving part connected to the vibrator for mechanical movement thereby, so that the movement of said part causes impulses in the electro-mechanical means, an electric circuit including the electro-mechanical means, means for amplifying the impulses developed in the circuit by the vibrators, sound translating means for translating the impulses into sounds corresponding thereto, and electro-mechanical means for giving a single impulse to each vibrator.

2. In a musical instrument, the combination of a plurality of vibrators capable of vibrating at different periods respectively, corresponding to the notes of a musical scale, means including an electro-magnet adjacent each vibrator, a part mechanically actuated by the vibrator so that the vibration of said part develops impulses in the electro-magnet, an electric circuit connected with the electro-magnet, means for amplifying the impulses developed in the circuit by the vibrators, sound translating means for translating the impulses into sounds corresponding thereto, a key corresponding to each vibrator, and an electro-magnet adjacent each vibrator controlled by its corresponding key and operating to give the vibrator a single impulse when the key is depressed.

3. In a musical instrument, the combination of a plurality of vibrators constructed to vibrate at different periods respectively, corresponding to the notes of a musical scale, an electro-magnet having a coil adjacent each vibrator and having an armature mechanically connected with the vibrator so as to be vibrated thereby, an electric circuit connected with the said coil, means for amplifying impulses developed in the circuit by the vibrators, sound translating means for translating the impulses into sounds corresponding thereto, a key corresponding to each vibrator, and an electro-magnet adjacent each vibrator controlled by its corresponding key and operating to give the vibrator a single impulse when the key is depressed.

VICTOR H. SEVERY.
